UNITED STATES PATENT OFFICE.

WILLIAM H. ARNOLD, OF STOCKTON, CALIFORNIA.

CAN-OPENING INSTRUMENT.

1,095,369.

Specification of Letters Patent.

Patented May 5, 1914.

Application filed May 17, 1913. Serial No. 768,265.

To all whom it may concern:

Be it known that I, WILLIAM H. ARNOLD, a citizen of the United States, residing at Stockton, in the county of San Joaquin, State of California, have invented certain new and useful Improvements in Can-Opening Instruments; and I do declare the following to be a full, clear, and exact description of the same, such as will enable others skilled in the art to which it appertains to make and use the same, reference being had to the accompanying drawings, and to the characters of reference marked thereon, which form a part of this application.

15 This invention relates to improvements in can opening instruments and is especially adapted to supplant the present form of slotted key used for opening cans provided with projecting lips, the slot in which 20 key is closed at both ends and necessitates the using of a separate key for each can, since the key cannot be disengaged from the cover of the can after the same is removed from the can.

25 My invention provides a means whereby one instrument may be used for opening an indefinite number of cans and also provides a means for more easily opening the cans and an immediate and prompt removal of 30 the key from the cover when the cover is removed from the can.

Figure 1 is a front elevation of the complete instrument. Fig. 2 is a sectional view taken on a line X—X of Fig. 1. Fig. 3 is a 35 view of a modified form of instrument from that which is shown in Fig. 1.

Referring now more particularly to the characters of reference on the drawings, the numeral 1 designates the handle of the instrument and the instrument proper comprises a plate or blade 2 suitably fitted into the handle 1 and provided in its lower end with a cut-in slot 3. The edges 40 of the member 2 taper from the handle member gradually down to the end at which is located the slot 3. The blade 2 may be provided on one side at one edge with a curved shoulder 4 and on the other

side and at the opposite edge with a curved shoulder 5 and at the upper end of the member 2 is an annular ring or flange 6.

50 In practice the instrument is used by inserting the projecting lip of the cover of the can into the slot 3 and then the instrument is turned in such a manner as will unseal 55 the top of the can around the member 2 in the usual manner which will permit the top of the can to be completely removed; then by working the instrument slightly in the reverse direction, this will loosen the wound 60 tin on the instrument and then by reason of the tapered sides of the member 2 and the opened end of the slot 3 the instrument may be withdrawn from engagement with the cover of the can and is ready for further use. 65

The curved sides 4 and 5 and the annular ring 6 engaging the edges of the can when the opening operation is first commenced permits of the initial breaking away of the cover of the can more easily than if such 70 elements were not present, although the instrument can be used without these elements if desired.

Fig. 3 shows the instrument as it would appear without the said elements 4, 5 and 6. 75 As can be readily seen, by having the opened slot 3 and the tapered sides of the member 2 I have overcome the objection in the use of the closed slots in the keys now commonly employed and produced an instrument capable of repeated use in the opening of cans. 80

From the foregoing description it will be readily seen that I have produced such a device as substantially fulfills the object of the invention as set forth herein.

85 While this specification sets forth in detail the present and preferred construction of the device, still in practice such deviations from such detail may be resorted to as do not form a departure from the spirit of the 90 invention.

Having thus described my invention what I claim as new and useful and desire to secure by Letters Patent is:

A device of the character described 95 comprising a handle member, a flat blade on

2
said handle member having a slot cut inwardly from its outer end, a curved shoulder on one side of said blade at one edge thereof, a curved shoulder on the other side of said 5 blade and at the opposite edge thereof, there being a portion of the flat surface of said blade disposed between each of said curved shoulders and said slot, as described.

In testimony whereof I affix my signature in presence of two witnesses.

WILLIAM H. ARNOLD.
